UNITED STATES PATENT OFFICE

WALTER J. HUGHES, OF CHICAGO, ILLINOIS, ASSIGNOR TO GENERAL ZEOLITE CO., OF CHICAGO, ILLINOIS, A CORPORATION OF ILLINOIS

FLUID PURIFYING DEVICE

Application filed April 9, 1931. Serial No. 528,746.

In the art of steam separation or purification as it is coming to be known, the early devices were installed in the steam line adjacent to the engine or other apparatus in 5 which the steam was used. This was because superheaters had not come into general use at that time. The early problem was one of protecting the prime mover from slugs of water discharged from the boiler with the 10 steam and also from water formed by condensation during transmission of the steam from boiler to engine. With present-day general use of superheaters, the need for purification is not lessened, but the point of applying the separator or purifier is changed 15 to precede the superheater.

The advantages are obvious in that when wet and impure steam is delivered to a superheater, some heat is consumed for evaporation instead of all being used to raise the temperature above that at the saturation point. Also the impurities clog the superheater and reduce its heat transmission efficiency.

20 Superheaters are usually installed in the path of the furnace gases within the furnace setting of a boiler. In order to precede them the steam purifier has commonly been installed within the steam space of the boiler 25 and connected to the boiler outlet. While this practice has prevailed for several years and still is followed to some extent, further development in steam generation is bringing about a second general change. While the 30 steam drums of boilers are not being materially increased in size, the steam generating capacities in proportion to drum sizes are being doubled and tripled. Purifiers must increase in size according to the amount of 35 steam generated so that space for proper installation within the boiler is becoming generally inadequate for the purifier and for access to same.

A purifier installed within the boiler and 40 known as the internal type, has to fit within the space above the water line in a comparatively long and small diameter drum. Its shape therefore is long and narrow, in many cases requiring careful attention to steam 45 flow distribution to prevent overloading of

portions adjacent to the outlet. In some cases an auxiliary drum has been provided for the steam purifier but this as heretofore done involves considerable expense and requires space that is in many cases not readily 55 available, together with piping difficulties.

While the construction herein disclosed is suitable for steam at high pressure, it is also applicable to steam under low pressure and to the purification of exhaust steam where 60 the pressure may be subjected to more or less violent pulsation, such as occurs with the exhaust from a reciprocating engine. This construction is also suitable for the purification 65 of various gases as well as for steam.

This invention has several objects. One object is an arrangement that requires a much smaller and less expensive pressure vessel or casing. This is accomplished by the use of a cylindrical wall within the casing for 70 mounting the purifying element, instead of a flat circular plate across the vessel as heretofore used, together with an improved type of purifying element and method of mounting same. In vessels of the same diameter 75 and approximately the same height, the cylindrical wall presents much more surface area than a flat cross plate to which the purifying element has been heretofore attached and so greater capacity in the same space or equal 80 capacity in a smaller casing.

Thus in a casing 5 ft. in diameter and 4 ft. in height, a flat cross plate provides a gross area of only about 20 sq. ft. to which a purifying element may be fastened. In the same 85 size casing, an inner cylindrical surface for a purifying element may be 4 ft. in diameter and 4 ft. high providing about 48 sq. ft. of gross area or more than double that of the flat cross plate. In other words, to provide 90 equal element area in a flat cross plate, the casing would have to be about 8 ft. in diameter or be made longer in proportion.

Since an increase in diameter requires the 95 use of heavier construction in pressure vessels the cost thereof increases more rapidly than the size increase. Thus both the space required and the cost of construction are materially reduced by my arrangement where- in I utilize a cylindrical inner wall for sup- 100

porting the purifying element. Also the capacity secured for the same size casing is much greater since the capacity is in proportion to the element area.

Another object is the elimination of flat plates placed crosswise of the pressure vessel. Such plates are subjected to pressure variations which tend to weave them, causing distortion and loosening of joints, also loosening and misalignment of the purifying element attached to same. Where the pressure variations are considerable or continue over long periods or are frequent, as with pulsating flows, cracking of the plate may occur, due perhaps to the metal becoming fatigued. Failures of this kind cannot be totally avoided even with very heavy and costly flat construction. The use of an inner cylindrical partition for attachment of the purifying element avoids these difficulties and at the same time construction may be of much lighter and less costly material.

Another object is the provision of a symmetrical arrangement of the purifying elements with reference to the steam inlet and of ample flow passage for the steam beyond the elements so as to prevent any tendency to short circuit or to overload any part of the purifying surface. The arrangement shown is ideal in these respects and this advantage is gained in a construction at once compact, readily accessible and of lower cost.

Since the inner chamber of this construction is cylindrical and of much larger cross section area than the inlet pipe, it serves also as an expansion or stilling chamber and thus any larger slugs of liquid fall to the bottom without entering the purifying element. The element is thereby relieved of severe overloading and will in general work more efficiently.

By carrying the inlet pipe up into the chamber a simple and cheap drainage chamber is provided. With this construction the drainage chamber may be very large so as to hold large quantities of liquid. This avoids the need and expense of large drainage pipe and trap to take care of the large slugs or floods of liquid that are sometimes carried in for short periods. They can be held in this large space until there is time to drain out through ordinary sized pipe and trap. Also the flange on the side of the shell may be placed in any desired position so as to facilitate piping connections.

The vessel is easily entered through a suitable opening for placing of the purifying element sections of which there may be one or several tiers. Thus accessibility for cleaning, inspection and repairing is provided. The inner cylindrical wall may be entirely filled with purifying element sections or it may be partly blanked off so that extra sections may be later added to the purifier to take care of future load increases.

The purifying element sections are removable units of convenient size for easy handling and may be passed through the opening in the vessel provided for access to same. The sections slide into place in the cylindrical wall much the same as drawers, and when arranged in tiers the sections, which are rectangular in shape, provide triangular shaped corner spaces readily utilizable for the drainage of individual sections.

My improved purifier therefore presents the important advantages of larger capacities with smaller and less costly apparatus, having improved drainage facilities, greater accessibility, more rigid construction and requiring less installation space. Other advantages will be apparent to those familiar with conditions existing in the field to which my invention pertains.

Referring to the drawings, Figure 1 is a plan view of a preferred construction on section 1-1 of Figure 2. Figure 2 is a vertical section of Figure 1 on the line 2-2. Figures 3, 4, 5, 6, 7, 8 and 9 are details of the construction in which the same parts are designated by the same numerals.

In Figures 1 and 2, 10 is a suitable casing, 11 is an inlet, 12 is an outlet and 13 is an opening provided with a closure which may be used for access to the interior of the casing 10. Part 14 is a concentric wall attached to the top head of the casing 10 and 15 is a similar concentric wall attached to the bottom head of the casing 10 and projecting upwardly into same. The bottom of the casing 10 is provided with a drainage outlet 18 and the inlet nozzle 11 is provided with an upwardly extending skirt 16 surmounted by a buffer or baffle plate 17 which will serve to still or even the flow of fluid into the casing. The skirt 16 is extended sufficiently high to form a wall that will separate the inlet opening from the drainage space in the bottom of the casing 10.

To the bottom edge of wall 14 and the upper edge of wall 15 are attached two similar plates 19. The outer circular edges of the plates are attached to the walls 14 and 15 while the inner hexagonal or other suitably shaped edges conform to the shape of the inner chamber formed by the row or rows of removable purifying sections 20. The space between the upper and lower plates 19 may accommodate one row of purifying sections or it may accommodate two or more rows in tiers one above the other as shown in Figure 2.

When the purifier sections 20 which are rectangular in shape are in place in the purifier, they form with the walls 14 and 15 an inner chamber communicating with the inlet, or outlet as the case may be, and an outer annular space connected with an outlet, or the inlet as the case may be, depending upon the direction of flow of the fluid. In the case of the

construction illustrated, when the purifying sections are in place, the arrangement forms a hexagon the six corners of which are occupied by drainage members 21 which are wedge shaped.

5 Figure 3 shows a detail of the construction of each of the six corners indicating how the plates 19 are tied together by the hollow drainage members 21. The drainage members 21 are provided with properly positioned drainage ports 23. The lower plate 19 carries an opening immediately under each drainage member 21 and these openings carry pipes 22 with sealed bottom ends as illustrated in Figure 2.

10 Figure 4 shows a preferred form of purifying section comprised of plates or vanes 24 which are held in parallel relation to each other by rods on which there are spacers 25, there being one rod through each corner of the plates 24. Each section is completed at its ends by the flexible strips 26 which provide space for the nuts which go on the ends of the rods carrying the plates 24 and 25 spacers 25. These flexible strips 26 are sealing members enabling the sections to be pushed into place between two of the drainage members 21 in such manner that the fluid is caused to pass through the section comprising the plates 24 on which are the shaped passage members 27. These shaped passage members 27 are tubular and serve to collect moisture or other impurities from the fluid and permit it to be discharged to the bottom of the purifying section where it is collected in a drain pan 27-a as shown in Figure 5.

15 Figure 5 is an assembly of a top cover plate 28, a purifying section 20 and its drain pan 27-a as the three parts would appear when set in place between two of the drainage members 21. Figure 6 is a detail of the intermediate or top plate 28 with overhanging edges the front one of which has the extension lips 29-a. The ends are provided with drainage spouts or lips 29 which project through the drainage openings in the drainage member 21 when the top 28 is in place. (See Fig. 9.)

20 Figure 7 is a detailed view of the drainage pan showing the end openings 30, the angles 31 for supporting the purifying section 20 above the bottom of the pan, the stiffening edges, the rear one of which is notched at the back corners to fit the projecting edges 32 of the backs of the upright drainage members 21 shown in Figure 3. The forward corners are provided with the sealing lips 27-b.

25 A tier assembly is made up as follows:—A section 20, Figure 4, is set into one of the drain pans 27-a, Figure 7, in such manner that the sealing strips 26-a at the ends slide inside the ends of the drain pan 27-a. The assembly is pushed back into place on the lower plate 19 between two of the drainage

uprights 21. When in place the back corners of the assembly will rest against the back projecting edges 32 of the upright drainage members 21 and the drainage pan openings 30 will register with the drainage ports 23 in the drainage members 21 at the ends.

30 An intermediate top cover plate 28 as shown by Figure 6 is set on top of the purifying section, being dropped in to place in such manner that the projecting lips 29 are inserted in the corresponding drainage openings or ports 23 of the upright drainage members 21. This intermediate top cover plate locks the first lower section in place.

35 A second purifier section 20 is placed in its drainage pan 27-a and pushed into place on top of the top intermediate plate 28 of the first section inserted. In the same manner a second top intermediate plate is set in place on top of the second section so that its drainage lips 29 project into the second tier of drainage ports 23 in the upright drainage members 21. In this manner the second tier of any number of sections may be built up and locked in place but the uppermost section which slides under the uppermost plate 19 carries a top plate 35 as shown by Figure 8. This top plate is provided with sealing strips 32-a which engage the under surface of the upper plate 19. (See Fig. 3.)

40 The top or uppermost section is held locked in place by means of the removable fastener or lug 33 and the stud and nut 34 attached to the upright drainage member 21 as shown in Figure 3.

45 Figure 9 shows a portion of the construction illustrating how the tiers of purifying sections are built up and pushed into place like a set of drawers.

50 Referring to Figures 1 and 2, it will be noted that when the position of the connection 12 to the outer annular space between the wall of the casing 10 and the purifying element structure tends to cause uneven flow through the element, a semicircular or other shaped annular passage may be attached to the wall of 10, as the member 36. This member may carry spaced openings 37 aggregating a total area equal to or slightly less than that of the opening 12.

55 It will be understood also that the opening 11 may be at the top of the casing 10 instead of at the bottom, in which case the manhole opening 13 may be at the bottom. Obviously by reversing the sections 20 and making other adaptations the flow of fluid through the purifier may be in the opposite direction from that illustrated. In some cases it will be found advantageous to have a complete cylinder extending from the top to the bottom head of the casing instead of the upper and lower rings 14 and 15, the purifying sections being set into openings cut in this cylinder. In such case the drainage members 21 could be dispensed with and

other drainage means such as pipes provided. If there were but a single horizontal row of purifying sections drainage could advantageously be by a pipe leading directly from 5 pan 27—a the drainage members 21 and related parts being modified or omitted.

While I have shown and described in some detail a preferred form of construction embodying my invention yet it is to be understood that this is for exemplification and illustration only and that I do not limit myself to the particular arrangement shown. I am aware that many changes in details 10 may be made and will suggest themselves to 15 those skilled in the field to which this invention pertains.

I therefore do not propose limiting the patent granted except as necessitated by the prior art, short of the broadest interpretation 20 of the appended claims.

What I claim is:

1. In a fluid purifier comprising a vertical cylindrical casing, an inner wall forming an outer annular passage having an outlet 25 and an inner chamber having an inlet, a port in the said wall, a demountable purifying element adjacent to said port and means for equalizing the resistance to flow from the outer annular passage to the said outlet.

2. In a fluid purifier comprising a vertical cylindrical casing, an inner wall forming an outer annular passage having an outlet and an inner passage having an inlet, a port in the said wall, purifying means in connection 30 with the said port, the said means comprising removable tiered sections, vertical drainage passages common to the sections adjacent thereto, and means for equalizing the resistance to flow from the purifying element to the said outlet.

3. In a fluid purifier, a vertical cylindrical casing having an inner concentric wall having a port and forming a central subsidence chamber and an outer annular passage, an inlet 45 in the bottom of the said chamber the wall thereof extending vertically a substantial distance into the chamber, an outlet for the outer annular passage, purifying means adjacent to said port, means for draining the said purifying means to the bottom of the subsidence chamber and means for draining the said chamber.

4. In a fluid purifier, a vertical cylindrical casing having a ported inner concentric wall, a casing outlet on one side of the said wall, and a casing inlet on the other side, and removable means operatively covering each port for effecting purification of the fluid passing through each said ports.

5. In a fluid purifier, a vertical cylindrical casing having inlet and outlet openings, a concentric wall within the casing between the said inlet and said outlet, a port in the concentric wall, removable purifying means covering the said port, means for drainage of

the said purifying means, and an opening for removal of the said purifying means from the casing.

6. In a fluid purifier, a cylindrical casing, a poly-sided structure comprising purifying sections supported concentrically within the said casing, top, bottom and end closures for the said sections, the bottom and end closures being adapted to receive and convey drainage from the said sections, an inlet to and 70 an outlet from said casing and means comprising a cylindrical wall and the said closures for causing the fluid to pass through the said purifying section.

7. A fluid purifier comprising an outer 80 cylindrical casing having an inlet, an outlet, and a drain opening, an inner cylindrical structure extending from end to end of said casing, a demountable purifying element mounted in the wall of said inner structure, 85 drainage means for said element, the bottom of the casing serving as a drain chamber to receive separated impurities.

8. A fluid purifier comprising a vertical cylindrical casing having inlet, outlet and 90 drain openings, an inner cylindrical structure extending from end to end of said casing, a removable purifying section mounted in the said structure, sealing members attached to said section and bearing on said structure, 95 said section and said casing being provided with drainage means.

9. A fluid purifier comprising a cylindrical casing having inlet, outlet and drain openings, a cylindrical structure therein and extending from end to end thereof, a removable purifying element mounted in said structure and sealing members contacting with said structure and said element for preventing fluid by-passing said element.

10. A fluid purifier comprising an outer casing, an interior rigid structure comprising demountable purifying elements and extending from one end thereof to form an outer annular chamber and an inner cylindrical chamber, an outlet from said annular chamber, an inlet to said cylindrical chamber said inlet being substantially less in area than the cross section area of the inner cylindrical chamber.

11. In a fluid purifier having an outer casing provided with inlet, outlet and drain connections, a rigid inner structure extending from end to end thereof having demountable fluid purifying means mounted in the wall thereof, said structure dividing the interior of the casing into an annular outlet chamber and an inner cylindrical expansion chamber.

12. A steam purifier of the external type having a closed cylindrical casing provided with an internal structure extending axially therein and attached to the two ends thereof and forming an inner cylindrical chamber to provide an expansion space for the incoming steam, the bottom of said cylindrical

chamber serving as a receiver for separated impurities, said casing having an outlet and said expansion chamber having an inlet opening and a drain opening and demountable purifying elements mounted in the wall of
6 said structure.

13. In a fluid purifier, a cylindrical casing, an inner cylindrical wall attached to both ends of said casing to form an inner cylindrical chamber and an outer annular chamber, a
10 fluid inlet to one chamber and a fluid outlet from the other chamber, a port in said wall through which fluid must pass to flow from the said inlet to said outlet, a demountable purifying element operatively covering said
15 port and an opening in said casing for removal of said element, the inlet chamber being of substantially greater cross sectional area than the inlet thereto.

20 In testimony whereof I have hereunto sub-
scribed my name.

WALTER J. HUGHES.
